UNITED STATES PATENT OFFICE.

LYDIA B. THOMAS, OF KENNETT SQUARE, PENNSYLVANIA.

CHILD'S GARMENT.

1,411,816.

Specification of Letters Patent.

Patented Apr. 4, 1922.

Application filed May 24, 1921. Serial No. 472,172.

To all whom it may concern:

Be it known that I, LYDIA B. THOMAS, a citizen of the United States, residing at Kennett Square, in the county of Chester 5 and State of Pennsylvania, have invented new and useful Improvements in a Child's Garment, of which the following is a specification.

My invention relates to new and useful 10 improvements in a child's garment, and has for its object to construct such a garment that will be especially convenient for children under three years of age; that can be readily and conveniently laundered; that 15 can be easily changed to accommodate the different heights of a growing child; and that will have little or no stress or strain on any part thereof thus requiring less repair than most children's garments.

20 Another object of the invention is to produce such a suit of any desirable fabric, the different parts being of the same color or some parts one color and the other parts another color, the two principal parts comprising a body portion and a trousers portion, the former having a skirt section of sufficient length to permit the trousers portion being positioned relative to said body portion for changing the distance between 25 the shoulders of the body portion and the crotch of the trousers portion.

A further object of the invention is to produce a garment including a body portion and a trousers portion, said body portion 35 primarily consisting of a front body section having a skirt section extending below the normal waist line, two back body sections secured one to each of the outer edges of the front body section, the other or inner free 40 edges of the back body sections adapted to overlap and be temporarily secured to each other and sleeves attached to the arm holes, and a trousers portion primarily consisting of two front trousers sections secured together 45 along their inner edges and along their upper edges to the front body section above and below the normal waist line and two back trousers sections secured to each other along their inner edges and said back 50 trousers sections are secured to the front trousers sections along portions of their inner edges from the crotch to the lower edges thereof, the free outer edges of the trousers sections adapted to overlap and be tempo- 55 rarily secured to each other.

With these ends in view, this invention

consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a front elevation of a child's garment made in accordance with my invention.

Fig. 2, is a rear elevation thereof.

Fig. 3, is a view similar to Fig. 2 with portions thereof folded back to clearly illustrate the details of construction.

Fig. 4, is a reverse inverted face view of 75 the back trousers portion spread out in a flat position.

In carrying out my invention as here embodied, 2 represents the body consisting of a front body portion 3 having a skirt section 4 extending below the normal waist line which is in the region of the locality indicated by the numeral 5. The upper edge of the front body portion has a curved edge forming a portion of the neck opening or 80 collar band from which projects a shoulder edge 6 on each side thereof and from these edges project curved arm hole edges 7 leaving side edges extending the full length of the body portion above and below the normal waist line from the arm pit to the lower edge of the skirt.

To each of the side and shoulder edges is secured one of the two back body sections 8 and 9 forming side seams 10. These back 95 body sections each include a skirt 11 below the normal waist line and have the curved arm hole edges 12. The inner or normally free edges of the back body sections overlap and are temporarily fastened together by 100 means of buttons 13 carried by one of the sections as 9 and button holes 14 formed in the coacting or complementary section, said buttons and button holes being located between the normal waist line and the neck 105 opening.

If found desirable a collar 15 may be attached to the neck edges of the different sections and to the arm hole edges are secured the sleeves 16.

The reference numerals 17 and 18 denote the two sections of the front trousers por-

tion, said sections having portions of their upper edges rounded or arcuate in shape as indicated at 19 and the upper edges are secured to the front body portion and to the 5 skirts of the back body portion beyond the side seams as plainly shown in Fig. 3 and said front trousers sections are secured along their inner edges from their upper edges to the crotch as indicated at 20 the upper 10 parts of said sections forming a bib 21 extending above the normal waist line of the body. Below the crotch said sections 17 and 18 form leg parts 22.

The back trousers portion 23 comprises 15 two back trousers sections 24 and 25 secured together along their inner edges as at 26 from their upper edge to the crotch and below said crotch are produced the leg parts 27 the inner edges of these leg parts from 20 the crotch to their bottom edges are secured to the inner edges of the leg portions of the front trousers sections as indicated at 28, while the outer side edge of each of the sections 24 and 25 overlap the outer side edges 25 of the front trousers sections 17 and 18 and are adapted to be temporarily fastened there- to by means of buttons 29 carried by the front trousers sections and button holes 30 formed in the back trousers sections while 30 the upper edge of the back trousers portion formed by said sections is adapted to be temporarily fastened to the back body portion by means of buttons 31 carried by said back body portion and button holes 32 35 formed in the region of the upper edge of the back trousers portion.

From the foregoing it will be noted that I have devised a child's garment particularly adapted to be worn by children be- 40 tween the ages of approximately one and one-half years to three years or during that time that diapers have been dispensed with and when it is necessary to often set a child upon a nursery chair permitting the trou- 45 sers to be unfastened and for all practical purposes entirely removed without the necessity of removing the body and when said trousers are withdrawn they are unlikely to become soiled.

50 Another advantage is that the garment may be placed upon a child while standing making it unnecessary for said child to raise

first one foot and then the other which be- cause of their age and limited strength often causes such child to become unbalanced and fall. 55

It is also to be particularly noted that be- cause of the skirt formed with the body as the child grows the trousers may be removed from the body and again secured thereto in 60 a lower position so as to increase the distance between the shoulders and crotch to prevent the garment binding any part of the child's body and because the garment can be opened up to such an extent it simplifies both the 65 washing and ironing.

Of course I do not wish to be limited to the exact details of construction as herein shown as these may be varied within the limits of the appended claim without de- 70 parting from the spirit of my invention.

Having thus fully described my invention, what I claim as new and useful is:—

A garment including a body portion and a trousers portion, said body portion prima- 75 rily consisting of a front section having a skirt extending below the normal waist line, two back body sections secured one to each of the outer edges of the front body section, the inner or free edges of the back body 80 sections adapted to overlap and be tempora- 85 rily secured to each other, said body portion having arm holes and sleeves secured to the body portion along the edges of said arm holes, said trousers portion primarily con- 90 sisting of two front trousers sections and secured together along their inner edges and along their upper edges to the front body section above and below the normal waist line and to the back body sections for a short 95 distance beyond the side seam, and two back trousers sections secured to each other along their inner edges and to the front trousers sections along their inner edges from the crotch to the lower edges thereof, the outer 100 edges of the trousers sections adapted to overlap and be temporarily secured to each other, and means for temporarily securing the upper edges of the back trousers sections to the back body sections.

In testimony whereof, I have hereunto affixed my signature.

LYDIA B. THOMAS.
